UNITED STATES PATENT OFFICE.

JOHN F. STECKENREITER AND FRANK J. STECKENREITER, OF BROOKLYN, NEW YORK.

WINDOW CONSTRUCTION.

1,420,457.

Specification of Letters Patent. Patented June 20, 1922.

Application filed November 20, 1920. Serial No. 425,486.

To all whom it may concern:

Be it known that we, JOHN F. STECKENREITER and FRANK J. STECKENREITER, citizens of the United States, and residents of the city of New York, borough of Brooklyn, in the county of Kings and State of New York, have invented a new and Improved Window Construction, of which the following is a full, clear, and exact description.

10 This invention relates to window constructions, and has for an object the provision of a window construction in which the greatest possible lighting area is provided for a given strength of window.

15 Another object resides in the provision of means whereby all parts of the window sashes are open for inspection and painting at all times.

20 A further object resides in the provision of means whereby there are no enclosed portions on the window sashes in which condensation can take place and rusting result.

25 A still further object resides in the provision of a window construction in which the tendency of the sashes to rattle is reduced to a minimum.

Another object resides in the provision of a structure which is to a maximum degree weather and draftproof and fireproof.

30 A further object resides in the particular construction and arrangement of parts hereinafter described and claimed and shown in the accompanying drawings.

35 Hitherto, some window sashes have been made of sheet metal and have involved hollow enclosures in which moisture may collect and cause rusting within the enclosures, and the metal becomes eaten through by this rusting action. Moreover, the lighting area 40 provided is reduced. Furthermore, because of the fact that the windows are hollow within, these enclosed portions cannot be inspected readily and painted to prevent the rusting action above mentioned.

45 Our invention relates to certain features of construction in which the above-mentioned objections are eliminated. We provide a window frame and sash portion which are made of standard stock metal forms, such 50 as channel bars, which can be assembled in the desired form and suitably connected together. Channel sections thus being used, the sashes are made narrower but of con-

siderably heavier metal, while they are approximately of the same weight per lineal 55 foot. The sashes thus being made of heavier metal, makes them practically indestructible under ordinary use and wear, and the sections being open, they are readily inspected at any time, and, where necessary, as readily 60 painted to prevent rusting. Another most important feature of the invention lies in the provision of a resilient strip at each side of each sash and between each sash and the channel member or groove along which it is 65 adapted to slide. These resilient strips are intended to accomplish several important things. They are intended to make the sliding movements of the sash smoother by reducing friction; to make the construction 70 weatherproof, thus obviating the necessity of weatherstrips, and to make the window rattle-proof.

A further feature resides in the fact that by using stock channel bars or similar forms 75 we are able to obtain the same strength for the window construction while using smaller sized metal members, so that the lighting area of the sash is considerably increased for the same strength of window.

80 Other features of the invention will be apparent from a consideration of the following description when taken in connection with the drawings.

The invention is illustrated in the drawings, of which—

Figure 1 is an elevation of the window sash with the frame in position:

Figure 2 is a section taken on the line 2—2 of Figure 1; and

Figure 3 is a section taken on the line 3—3 of Figure 1.

As shown in Figure 3, this metal construction is used in connection with the ordinary wall or opening 1 in which the window frames are disposed. These frames are, as shown in the figure, made of vertically extending channel bar members 2 which are connected to similarly-shaped channel bar members 3 in such a manner as to form a vertically extending hollow jamb. These frames are built into the walls of the building adjacent the window aperture and are connected together either by welding, riveting or bolting at their abutting portions. 95 Across the top of the window opening a 100

2
lintel frame member is provided in the form of a channel member 4 with the open portion abutting the upper part of the wall of the window aperture. The opposite ends of this channel member 4 may be suitably connected to the upper ends of the vertically extending jamb members above mentioned. The bottom portion of the frame, extending between the vertical sash portions, is made in the form of a sill. This sill member is in the form of a metal channel member 5. This sill is connected at its end portions to the vertically extending frame members in any suitable manner, such as by riveting or by bolts. The upper face of the sill member 5 is formed with the usual outwardly sloping surface 6, an intermediate surface 7 and an inner horizontal flat surface 8. The surface 7 is separated from the surfaces 6 and 8 by vertically extending shoulder portions 9 and 10, which are provided for a purpose hereinafter to be described.

On the inner face of each of the vertically extending frame members are disposed sash guide members along which and between which the window sashes are adapted to slide. The inner and outer sash guide members are shown in the form represented by the numeral 11 and may be connected to the frame members in any suitable manner. These are made of metal of any stock form desired. The intermediate sash guide members, as represented by the numeral 12, are metal bars of the required dimension. Channel bar 3 is connected to the extensions of the sides of the vertically extending frame member 2 at 29 and 30. These two vertically extending projections, by being built into the wall, act as two continuous anchors 40 to hold the window rigidly in place.

In the channel portions formed between the members 11 and 12, the window sashes A and B are adapted to slide in the usual manner. The upper window sash is represented by the letter A and the lower, by the letter B. Each of these sash members comprises rails and stiles. The rails of each sash are in the form of metal bars, represented by the numerals 13 and 14, with the channel portion facing outwardly. Similarly, the stiles of each sash are channel bars 15 and 16. These stiles and rails are suitably connected at their abutting end portions in any desired manner, such as riveting or by being welded together. The window panes 17 are held in position in the rectangular opening between the stiles and rails by being disposed between metal bars, such as 18, which may be connected to the rails and stiles in any desired manner.

It will be observed that the rails and stiles are formed of channel members of such dimensions as to give them any desired strength and yet, at the same time, form a window sash which has no enclosed portions

within which moisture may form to cause the metal to rust. Practically the entire metal surface of the sash is open for inspection, and can be painted whenever it is necessary. By reason of the use of stock channel forms, any desired strength and weight of window sash may be obtained by the use of members which are smaller in size than hitherto has been the case, so that the light opening is proportionately increased.

With respect to the upper frame A, it will be observed in Figures 2 and 3 that there is disposed between the sides of the stiles 15 and 16 of this sash and the vertically extending sash guide members 11, a thin resilient strip of metal 19, preferably phosphor bronze, although any other suitable material may be used. This strip may be secured, if desired, between the sash guide member 11 and the vertically extending portion of the frame, such as the member 2, or may be connected in position in any other desired manner; the idea being that this strip will bear resiliently against the rear face of the stiles of the sash and by reason of its resiliency will prevent any lateral vibration of the sash and, at the same time, make a reasonably tight joint so as to make the structure weatherproof. This strip, with respect to the upper sash A, extends from the top of the frame opening to a point below the bottom of the upper sash when in its upper position, as shown in Figure 2. A similar set of strips 20 is provided between the metal bars 12 and the rear of the lower sash B. These strips are shown in Figures 2 and 3. The sets of strips 20 extending from the bottom of the sill member 9 to a point above the upper end of the sash B, when the sash B is in its normal closed position, as seen in Figure 2.

It will be noted that the bottom channel member 21 for the lower rail of sash B has depending side portions one of which is longer than the other. These side portions, when the window sash B is in its closed position, are adapted to contact tightly with the shoulders 9 and 10, previously mentioned, on the sill 5, whereby a very tight contact is made between the rail and the sill along two edges. To provide a tight weatherproof joint between the lower rail of the upper sash A and the upper rail of the lower sash B, these rails have applied to them channel bars, such as 22, each of which has two laterally extending faces, one of which, 23, is longer than the other, 24. The disposition of the long and short faces of these channel members 22 are reversed on the upper and lower rails, above mentioned, so that when the sashes A and B are in their closed position these long and short faces of the channel members contact with each other, as shown in Figure 2, to make an exceedingly tight joint, which is draft-

and weatherproof. However, although this joint is tight, when the windows are separated there is presented on each rail a channel bar which is entirely open, having no enclosed places, and which can be inspected and painted readily without disassembling the parts. A finger lift of any suitable form, such as 25, is applied in the sash near the lower rail of the sash B. The windows are supported by chains 26 running over pulleys 27 and balanced by the usual sash weights 28 which are disposed within the frame members formed by the channel bars 2 and 3 above mentioned.

15 It will be observed by a consideration of this description that we have provided a window construction in which the window sashes have the desired strength with a maximum lighting area, and of which the 20 metal is so formed that no enclosed spaces exist, all surfaces being open so as to be readily inspected and painted. The fact that the entire structure of these windows, excepting the glass is made of ordinary 25 stock metal shapes, makes the window one of extreme simplicity; having no soldered or brazed joints or connections makes it positively fireproof; all sections being made of heavier metal than the hollow metal 30 windows of this type now in use, makes it practically indestructible through ordinary wear and use; the sections composing the sash being narrower, it gives a larger lighting area for any given size of window opening, and it is free besides from any condensation pockets that would cause any hidden 35 rusting, because all sections are open to inspection at any time. Furthermore, the resiliency of the resilient strip makes the 40 sliding movements of the window smoother and comparatively frictionless, besides making the window construction draft-, rattle- and weatherproof.

Again, the vertically extending frame 45 members 2 and 3, having the back edges of the front and rear sides projecting into the wall for the full height of the vertical frame members, gives the window frame the maximum of anchorage.

50 This metal window construction is highly advantageous and answers a real need when

considered in the light of all these advantages.

What we claim is:

1. A window sash construction having 55 stiles and rails, which comprises a weather-tight joint between adjacent rails when the window sashes are in closed position, which joint comprises U-shaped channel members, the base of one member fastened to the lower 60 rail of one sash and the base of the other channel member fastened to the upper rail of the other sash, the legs of the each U member extending horizontally outwardly toward the legs of the other U member, 65 one of the legs of each U member being shorter than the other, these legs being so disposed that the short leg of one member, when the sashes are in closed position, contacts with the long leg of the other member, 70 and vice versa, to provide two spaced contacting surfaces disposed in horizontal planes to make the joint air- and water-tight.

2. A window construction having a sill 75 formed of an integral single portion of cast metal having a pair of spaced, vertically extending shoulders thereon and downwardly and outwardly sloping surfaces adjacent each shoulder, a lower rail of 80 a window sash adapted to co-operate with the sill, said rail formed of a U-shaped channel member, the legs of the U lying in vertical planes closely adjacent the vertical planes of the shoulders and bearing against 85 the shoulders tightly when the sash is in its lower and closed position.

3. A window sash construction having 90 stiles and rails, which comprises a U-shaped channel member disposed on adjacent faces of adjacent stiles when the sashes are in closed position, the legs of each member extending outwardly from each other, one leg of each member being shorter than the other leg and reversely disposed relative to each 95 other so that they overlap to form two contacting horizontal surfaces when the sashes are in closed position to make the joint weather- and water-tight.
